United States Patent Office

Des. 195,195
Patented May 14, 1963

195,195

VEHICLE-SUPPORTED SHELTER

Wayne L. Hunter, 7th and Lisbon St.,
East Liverpool, Ohio

Filed Jan. 19, 1962, Ser. No. 68,371

Term of patent 7 years

(Cl. D14—3)

FIG. 1.

FIG. 2.

FIG. 3.

FIG. 4.

FIG. 5.

FIGURE 1 is a perspective view of a vehicle-supported shelter embodying my novel design, the broken-line showing of the vehicle being for the purposes of illustration only;

FIGURE 2 is a top plan view thereof;

FIGURE 3 is a front elevational view thereof;

FIGURE 4 is a rear end elevational view thereof; and

FIGURE 5 is a side elevational view thereof.

I claim:

The ornamental design for a vehicle-supported shelter, as shown and described.
